UNITED STATES PATENT OFFICE.

GUSTAVE C. WILHELCMI, OF CLEVELAND, OHIO.

SOUND AMPLIFIER.

Application filed June 9, 1926. Serial No. 114,745.

This invention relates to new and useful improvements in sound amplifiers and more particularly radiophone amplifiers for imparting a wider tonal range, enlarging the volume, and clarifying the tone of radiophone sound waves, providing a simple compact, attractive structure preferably of wood embodying in combination with sound boxes a radiophone communicating with an elongated offset tortuous sound passage of gradually expanding cross sectional area having a concentric outlet emanating the spirally directed sound waves forwardly and radially providing maximum and efficient acoustic range of the amplifier.

Other objects and features of the invention will be hereinafter pointed out and described.

In the drawings:—

20 Fig. 1 is a front elevation of the amplifier.

Fig. 2 is a similar view with the front wall and mouthpiece removed.

25 Fig. 3 is a rear elevation with the rear wall removed.

Fig. 4 is a detail view of the tone regulating filler strip removed.

Fig. 5 is an edge view thereof.

30 Fig. 6 is a sectional view on line 6—6 of Fig. 1.

Fig. 7 is a section on line 7—7 of Fig. 2, with the front wall and mouthpiece applied.

Fig. 8 is a section on line 8—8 of Fig. 2.

35 Fig. 9 is a section on line 9—9 of Fig. 2.

Referring specifically to the drawings, the amplifier apart from the radiophone is preferably of wood construction providing richness and clarity of tone and is supported on a base 5 removably secured by screws to the curved side legs 6, front wall 7 and back wall 8 supporting between them the cylindrical amplifier body 9 comprising annular rings 10 and 12 and a mouthpiece 14 having a concentric bell-shaped outlet 15 flaring forwardly and outwardly to the front through an opening 16 in front wall 7. The inner restricted end 17 of outlet 15 opening through the rear of mouthpiece 14 is concentrically disposed relative to the rings 10 and 12.

50 The joint 18 between mouthpiece 14 and ring 12 is offset as at 19 and an internal groove 21 is provided at joint 20 between rings 10 and 12 for receiving a disc-shaped partition 22.

As shown in Figs. 3 and 6 a convolute or spiral-shaped sound passage wall indicated generally at 23 comprises an annular inner side wall surface 24 concentric with the center of rings 10 and 12, and an outer side wall surface 25 of one convolution convolute with the center of rings 10 and 12. The ends of the convolute wall 25 are positioned at the bottom thereof below the center of the convolute, the end indicated at 26 having the larger radius and the end indicated at 27 having the shorter radius. As viewed in Fig. 3 an extension wall 28 is provided having its lower and upper sides 29 and 30 extending substantially horizontally to the left from the convolution wall ends 26 and 27 respectively, to the inner side 11 of ring 10. The convolute wall 23 and extension 28 are suitably secured to partition 22 and extend against rear wall 8 providing a sound box 31 between the annular wall 24, partition 22 and rear wall 8.

70 A filling strip 32 of tapering cross sectional area having an outer face or wall 33 is suitably secured to partition 22 between ring wall 11, convolute wall 25 and extension wall 29, having the thicker end 34 positioned at the meeting point of ring wall 11 and extension wall 29, and the reduced end 35 extending approximately to the height of the ring center.

75 An opening 36 is provided in partition 22 having its bottom edge 37 flush with extension top side 30, side edges 38 and 39 flush with a portion of ring wall 11 and convolute wall 25 and a horizontal top edge 40 spaced from the lower edge 37.

80 A sound passage 41 of gradually expanding cross sectional area is formed by filler wall 33, extension wall 29, ring wall 11, rear wall 8, convolute 25 and partition opening 36, having the smaller cross sectional area thereof at the end 34 of filler strip 32 and the larger cross sectional area at partition opening 36.

85 A block 42, suitably secured between ring 10 and 12, side 6 and back wall 8, has an annular recess 43 in its bottom side and is tapped as at 44 communicating with an opening 45 in the block which communicates through an opening 10' in ring 10 with the reduced end of the sound passage 41. The screw threaded neck 47 of a radiophone or microphone 46 is threaded into tap 44, the recess 43 receiving the shoulder of the 90

105

110

radiophone casing. The radiophone lead wires 48 may be led out of the rear wall 8 and connected to the radio receiving set.

Referring to Fig. 2, a wall indicated generally at 49 suitably secured to partition 22 and extending between the partition and mouthpiece 14, has a horizontal bottom wall portion 50 flush with partition opening edge 40 and an intersecting wall 51 convolute to the center of ring 12, having its opposite free end 52 extending in a substantially horizontal plane with the ring center. The portion of wall 51 at partition opening 36 is flush with the opening edge 39. The end 52 of wall 51 meets a semicircular wall 53 concentric with ring 12 and lying flush with the lower half edge of the restricted outlet opening 17. The wall 53 is continued upwardly curving over the ring center as at 54 and terminates against ring 12 as at 55. An upper inclined wall 56 forming a chord with ring 12 together with partition walls 22 and mouthpiece 14 provides a sound box 57. The partition opening 36, wall 50, convolute wall 51, ring 12, partition 22, mouthpiece 14, walls 53 and 54 provide a sound passage of gradually expanding cross sectional area, enlarging from partition opening 36 to walls 54, 53 and outlet 17.

When the amplifier is connected to a radio receiving set and operated, the sound waves from the radiophone diaphragm pass through the casing neck 47, block opening 45, ring opening 10', sound passage 41, partition opening 36, and the front sound passage adjacent the walls 51 and 54 and are discharged through outlet 15, the sound waves enlarging in volume and tone and clarifying as they pass through the gradually expanding cross sectional area of the continuous sound passage and pass the sounding walls of the sound boxes 31 and 57. The curved walls 54 and 53 direct the sound waves spirally through the flared outlet 15.

The radiophone 46 may be attached centrally at the rear wall 8 or at the bottom of ring 10 if desired with a suitable connecting passage to the passage 41.

The tone of the amplifier may be regulated or adjusted by varying the length and tapering thickness of the filler strip 33, providing a fine tone of wide range. The compact arrangement of the sound passage and sound boxes provide an extra long travel of the sound waves within a structure occupying a minimum of space. The sound passage may be lengthened by providing additional partitions and varying the cylinder diameter.

The outer parts of the amplifier may be constructed of suitable wood to match any furniture. The partition 22, walls 23, 28, 49, filler strip 33 and block 47 are preferably of violin spruce, poplar, birch or like

woods to impart clearness and fineness of tone amplifying at the sound boxes.

The amplifier is adaptable for use in connection with any type of sound producing or reproducing apparatus.

While I have shown and described one embodiment of my invention, obviously various changes in the proportions and details of construction may be made within the scope and spirit of the appended claims.

I claim:

1. A sound amplifier comprising a casing having front and rear convolute tapered sound passages in parallel planes, the larger end of the rear passage communicating with the smaller end of the front passage, the rear passage having a peripheral inlet and the front passage having an enlarged axial outlet.

2. A sound amplifier comprising a casing having front and rear convolute tapered sound passages in parallel planes, the larger end of the rear passage communicating with the smaller end of the front passage, the rear passage having a peripheral inlet and the front passage having an enlarged axial outlet, the casing having therein sound boxes adjacent said passages respectively.

3. A sound amplifier comprising a casing having front and rear convolute tapered sound passages in parallel planes, the larger end of the rear passage communicating with the smaller end of the front passage, the rear passage having a peripheral inlet and the front passage having an enlarged axial outlet, the casing having therein an axial sound box around which the rear passage extends, and a peripheral sound box adjacent the outer wall of the front passage.

4. A sound amplifier comprising a casing having therein a plurality of sound passages each of which is convolute in form around a common axis, said passages being located in parallel planes with a partition therebetween, said passages communicating with each other through an opening in said partition, one passage having an inlet at the end opposite said opening and the other passage having an outlet at the end opposite said opening.

5. A sound amplifier comprising a casing having therein a plurality of sound passages each of which is convolute in form around a common axis, said passages being located in parallel planes with a partition therebetween, said passages communicating with each other through an opening in said partition, one passage having an inlet at the end opposite said opening and the other passage having an outlet at the end opposite said opening, said inlet being at the periphery of the casing and said outlet being at the center of the casing.

6. A sound amplifier comprising a circular casing having curved walls therein form-

ing two convolute passages extending around the axis of the casing, said passages having a partition therebetween and occupying parallel planes on opposite sides of said partition and communicating with each other through an opening in said partition, one passage having an inlet at the end opposite said opening and the inner wall of said passage forming a circular sound box at the 10 axis of the casing, and the other passage having an axial outlet at the end opposite said opening.

7. A sound amplifier comprising a circular casing having curved walls therein forming two convolute passages extending around the axis of the casing, said passages having a partition therebetween and occupying parallel planes on opposite sides of said partition and communicating with each other 15 through an opening in said partition, one passage having an inlet at the end opposite said opening and the inner wall of said passage forming a circular sound box at the axis of the casing, and the other passage 20 having an axial outlet at the end opposite said opening, the casing also having therein a sound box between its circular wall and the wall of the last named passage.

8. A sound amplifier comprising a circular casing, a rear wall, a front mouthpiece, 25 a cross partition spaced between said wall

and mouthpiece, forming front and rear chambers, and convolute walls in each chamber, between the rear wall and the partition and the mouthpiece and the partition, respectively, forming rear and front convolute 35 passages communicating with each other through an opening in said partition, the rear passage having a peripheral inlet, and the front passage having a central outlet to 40 said mouthpiece.

9. A sound amplifier comprising a casing having tapered therein a passage gradually expanding in size from a peripheral inlet to a central outlet, said passage being in the 45 form of two adjacent spirals in parallel planes, with a partition between having an opening connecting the spirals.

10. A sound amplifier comprising a casing having tapered therein a passage gradually 50 expanding in size from a peripheral inlet to a central outlet, said passage being in the form of two adjacent spirals in parallel planes, with a partition between having an opening connecting the spirals, the casing 55 having a sound box therein located centrally of one spiral, and another sound box outside of the other spiral.

In testimony whereof, I do affix my signature.

GUSTAVE C. WILHELMI.
